[57] **CLAIM**

The ornamental design for a floating object game, as shown and described.

DESCRIPTION

FIG. 1 is a perspective view of a floating object game showing my new design;

FIG. 2 is an elevational view thereof;

FIG. 3 is a bottom plan view thereof; and,

FIG. 4 is a top plan view thereof.

The broken line showing of base and alternate position of the inside ball is for illustrative purposes only and forms no part of the claimed design.
